UNITED STATES PATENT OFFICE.

RUDOLF BAUMANN, OF OERLIKON, SWITZERLAND.

SELF-HEATING CRUCIBLE-FURNACE.

SPECIFICATION forming part of Letters Patent No. 608,747, dated August 9, 1898.

Application filed December 31, 1897. Serial No. 665,050. (No model.) Patented in Switzerland February 17, 1897, No. 13,540.

To all whom it may concern:

Be it known that I, RUDOLF BAUMANN, a citizen of the Republic of Switzerland, residing at Oerlikon, near Zurich, canton of Zurich, Republic of Switzerland, have invented a certain new and useful Improvement in Crucible-Furnaces; and I declare the following to be a full, clear, and exact description of the invention, such as will enable others skilled in the art to which it pertains to make and use the same, reference being had to the accompanying drawings, which form a part of this specification.

This invention has been patented in Switzerland under No. 13,540, dated February 17, 1897.

My invention relates to crucible-furnaces, and has for its object to improve the general construction of such a furnace and render it easier of manipulation and more effective in operation.

In the drawings, Figure 1 is a side elevation of my furnace in normal position, the inclosing casing being shown in section. Fig. 1^a is a detail. Fig. 2 is a plan view of the mechanism shown in Fig. 1. Fig. 3 is a view similar to Fig. 1, showing the crucible-furnace in tilted position. Fig. 4 is a vertical section of the furnace with heater; and Fig. 5 is a plan of the furnace, the heater and top plate being removed.

Similar letters of reference represent similar parts in all the views.

A, Fig. 4, represents the crucible-furnace, having a jacket of sheet or other metal A³, provided at the base with an annular frame A' and at the interior side with a lining A² of refractory material.

V is the grate supporting the fuel.

W is the crucible-stand, with the projection w catching into a recess of the crucible A⁴.

X X', Figs. 4 and 5, are segments of refractory material placed between the lining A² and the crucible A⁴. By means of the segments X X' and the projection w of the stand W the crucible is secured in its position when the furnace is tilted. The space between the crucible A⁴ and the lining A² is filled up with burning coke. a is the spout, and r the gutter, arranged in the segment X' and in the lining A².

Y is the perforated top plate of chamotte.

The heater consists of the jacket T, with refractory lining t³, of the curb-ring t², of cast-iron, secured to the lower end of the jacket T and provided with the refractory lining t⁴ and with studs t⁵ to secure the lining t⁴, and of the tube U, of graphite, supported by the coat t⁶. The interior wall of the tube U forms the smooth continuation of the interior-lined and conical wall of the jacket T. By removing the lining t⁴ the tube U, when destroyed, may be removed and replaced by a fresh one.

t⁷ are ears into which rods may be set in order to carry away the heater.

The crucible-furnace A sets upon the well-known air-chamber B, Figs. 1 and 2, and possesses laterally and on a level with the kennel a pivots a', journaled in supports C, secured at the top of the chamber B. Owing to this arrangement the kennel a always remains in about the same distance from the level D, while the crucible-furnace, by means of suitable devices, may be tilted about the pivots a' and the contents of the crucible A⁴ discharged into molds placed upon the level D in front of the furnace.

The means for tilting the crucible-furnace A are the following: A hand-wheel F, Figs. 80 1 and 2, is secured to the top of the vertical shaft E and a worm G to the lower end of this shaft. The worm G actuates the worm-wheel H and pinion j. On opposite sides of the air-chamber B there is a beam K K', which beams are secured to the shaft M, journaled in brackets L. One of these beams K carries a toothed segment k, which gears into the pinion j. N N are links hinged at one end to the beams K K' and pivoted at the other end to the pivots a², fixed to the crucible-furnace A. The back ends of the beams K K' are connected by means of the cross-bar O, Figs. 1 and 2, on which the rollers P are loosely mounted. Q Q are arms secured to the shaft S, journaled in brackets R. The opposite ends of these arms are connected by means of the cross-bar S' and rest on the rollers P. A counter-weight S² formed by a series of plates and designed to balance the crucible-furnace is hung on the cross-bar S'.

When the crucible-furnace A is tilted about the pivots a', the leverage at which the weight of the furnace acts in relation to the pivots

a' increases and reaches the maximum when the furnace arrives in the horizontal position. In a correspondent rate also increases the leverage at which the counterweight *S²* acts upon the beams *K K'* by means of the arms *Q Q*.

x, Fig. 1, shows the leverage at the beginning of the tilting motion, and *y*, Fig. 3, represents the leverage when the furnace is tilted 10 to its highest position. Owing to this arrangement it is not necessary to drive the hand-wheel *F* with greater force when the furnace *A* approaches the horizontal position.

The worm and wheel *G H* prevent the automatic falling motion of the raised furnace, so that the latter may be maintained in any position.

The smelting process is the following: The space between the crucible *A⁴* and the lining *A²*, Fig. 4, is filled up with burning coke. Hereafter the heater is placed upon the furnace in such a way that the lower opening of the tube *U* is situated somewhat over the opening of the crucible *A⁴*, a small intermediate space being thereby formed between the upper edge of the crucible and the lower edge of the tube *U*. After this the crucible and the heater are filled up with the metal to be melted. Now the kennel *a* is closed by 30 means of a clay plug and the blast introduced into the air-chamber *B* through the pipe *Z*, Fig. 1. The blast enters the crucible-furnace through the grate *V*, drives the coke-flames and gases between the segments *X X'* toward the top of the furnace, and forces the same to pass the heater and the charge contained therein. The flames and gases give to the charge a red heat, so that it becomes soft and will be pushed down into the crucible, where 40 it is melted. In this manner an exceedingly quick smelting process is obtained, and since the metal is exposed to the flames only to the red heat, but does not melt in the flames, this taking place in the crucible, the evaporation 45 of the easily-combustible alloys contained in the compositions of metal is avoided.

The large lower opening of the heater per-

mits admission of the coke-flames to all the portions of the charge contained in the heater.

Owing to the smooth continued inside of 50 the heater stoppage of the charge is avoided.

When the smelting process is finished, the heater is removed, the kennel *a* opened, the crucible-furnace *A* tilted, and the crucible discharged, whereupon the latter and the 55 heater may receive a new charge.

Z' is a door to permit admittance to the tilting device and to the air-chamber *B*.

Having as above fully described my invention, what I claim as new, and desire to secure by Letters Patent, is—

1. In combination, the casing, the crucible-furnace having a spout near its upper end, and pivots suitably journaled in the casing on a line with said spout, a pair of rocking 65 beams located in the casing, links connecting said beams with the furnace and means for operating said beams to tilt the furnace, substantially as described.

2. In combination, the casing, the crucible-furnace having a spout near its upper end, and pivots suitably journaled in the casing on a line with said spout, a pair of rocking beams located in the casing, links connecting said beams with the furnace, a toothed segment connected with said beams, a spur-wheel 75 engaging said toothed segment, a worm-wheel and worm for operating said spur-wheel, substantially as described.

3. In combination, a tilting crucible-furnace, the rocking arms having link connections to the crucible-furnace for tilting the same, and the levers having stationary pivots at one end and weights at the other, and having a sliding bearing connection with said 85 arms, substantially as described.

In testimony that I claim the foregoing as my invention I have signed my name in the presence of two subscribing witnesses.

RUDOLF BAUMANN.
